WO 2005018472 3/2005

Primary Examiner — Charles D Hanson

(74) Attorney, Agent, or Firm — UB GreensfelderLLP;
Brian Erkin Turung(57) **CLAIM**

The ornamental design for a bone plate, as shown and described.

DESCRIPTION

FIG. 1 is a front elevation view of a bone plate in accordance with the new design;

FIG. 2 is a top plan view of the bone plate of FIG. 1 showing a longitudinal reference line and a transverse reference line; FIG. 3 is a bottom plan view of the bone plate of FIG. 1; FIG. 4 is a cross-section view of the bone plate of FIG. 2 along the longitudinal reference line;

FIG. 5 is a cross-section view of a screw opening of the bone plate of FIG. 2 along the transverse reference line;

FIG. 6 is a front end plan view of the bone plate of FIG. 1; and,

FIG. 7 is a rear end plan view of the bone plate of FIG. 1.
